UNITED STATES PATENT OFFICE.

RICHARD SHEPHERD AND WALTER DALHEIMER, OF EINDHOVEN, NETHERLANDS, AS
SIGNORS TO GENERAL ELECTRIC COMPANY, A CORPORATION OF NEW YORK.

WIRE-COILING MACHINE.

Application filed December 3, 1924, Serial No. 753,738, and in the Netherlands January 29, 1924.

This invention relates to an improvement on the invention of application, Serial No. 756,564, for U. S. patent by Heinrich H. M. Reufel, Hendrick de Jong, and Willem G. F. Wentink which was filed December 17, 1924, and comprises a coiling machine for winding wire into helices, especially comparatively fine wire into close coils or helices. The machine according to the invention is particularly adapted for use in making helical or coiled filaments for electric incandescent lamps.

In machines of this kind commonly the helix is wound on a traveling mandrel which is subsequently removed in any suitable manner, for example, by dissolving in chemical preparations. Especially when helices of fine wire having a very small pitch are to be wound, it is not only highly important that the rotary winding heads for winding the wire on the mandrel should rotate uniformly but also that the mandrel should travel uniformly.

One of the principal objects of the present invention is to prevent irregularities in the movement of the mandrel.

As a rule, a wire, for example of steel, used for the mandrel, is wound off from a supply roll and wound on a second roll after the helices have been wound on it. The said wire will hereinafter be referred to as "mandrel wire". The wire that is helically wound on the said mandrel wire will be referred to as "winding wire".

In the machine according to this invention, the winding wire is wound in known manner on the traveling mandrel wire which prior and subsequent to the winding operation passes over and is driven by the surfaces of rotary members which are so driven that the parts of the surfaces engaged by the mandrel wire have a substantially equal velocity and which rotate about the same axis. According to the invention the surfaces of the rotary bodies may be cylindrical surfaces on the same feed roll. According to the invention devices are preferably provided which keep the mandrel wire taut prior and subsequent to its passing over the feed roll, and devices are also provided which prevent the mandrel wire from slipping on the rotary bodies, for example, along the rotary driving surfaces. For this purpose the unwound mandrel wire may be pressed into engagement with its corre-

sponding driving surface by a roller, whereas the wound mandrel wire may be pressed into engagement with its corresponding driving surface by an endless belt led over a system of pulleys, of which at least one is movable for tensioning the said belt.

The machine according to the invention may be provided with a number of winding heads and mandrel wires so as to permit of a number of helices being wound simultaneously. In such a machine the mandrel wires prior and subsequent to the winding operation preferably pass over the same feed roll, and the winding heads are preferably rotatable on vertical axes.

In this manner a machine is obtained, all members of which can be easily controlled during operation, especially if according to another feature of the invention the rotary winding heads with their corresponding devices and the rotary calendar with its corresponding devices are arranged on both sides of a vertical table fixed to the machine's framework.

In the machine according to the invention both the mandrel wire and the winding heads may be driven continuously to make a continuous helix or coil, but when helices of a determined length connected by straight ends of wire are to be made the winding heads may be stopped periodically or the mandrel wire may be moved periodically at an increased speed.

By periodically changing the speed of rotation of the winding heads or the traveling speed of the mandrel wire, helices of varying pitch may be made.

If in the machine according to the invention the winding heads are rotatable on a vertical shaft, each winding head may be provided with a conical surface which bears on a rotary cone, a device being provided for actuating said cone at a uniform velocity with such a construction.

Each winding head can be stopped at will, when the windings wire or the mandrel is broken. For example, the rotary winding head may be provided with a second conical surface, a rotary disc having a similar conical surface being provided which by screwing up and down can be moved over such a distance that on screwing up, the winding head is lifted off the rotary cone.

It is important that the driving surfaces

which are engaged by the mandrel wire prior and subsequent to the winding operation, be driven at uniform speed and with as little vibration as possible, as otherwise some of the advantages of the machine may be lost and also that the rotary winding heads are actuated regularly and without vibrations so that the ratio velocity of the mandrel wires and the winding heads is practically invariable and to this end the present invention comprises various devices to meet these requirements.

The frame of the machine to which the shaft for the feed roll and the other devices for moving the mandrel wire and the devices for winding the winding wire are fixed may, according to the invention, be so mounted as to be entirely clear of the driving mechanism, the latter being interlocked with those members of the machine that have to be driven by means of a belt only.

Furthermore, in order to prevent vibrations and irregularities in driving high speed winding heads, the latter are preferably actuated directly by means of a belt, and if desired the entire transmission of motion may be accomplished by means of one endless belt.

The accompanying drawing illustrates one form of a machine constructed according to the invention and having six rotary winding heads. In this construction both the mandrel wire and the winding heads are driven continuously. In the said drawings:

Figure 1 is a rear elevation of a machine according to the invention.

Figure 2 is a vertical section along the upper part of the machine.

Figures 3 and 4 are respectively a plan and a side elevation of the belt gearing of the machine according to the invention.

Figure 5 is a vertical section of the rotary winding heads of the machine.

Figure 6 is a plan of such a winding head.

The construction and operation of the machine is apparent from Figure 2 of the drawing. The mandrel wire 9 is wound on a slightly braked supply spool 7 pivoted to a housing 8 mounted on the main frame 1 of the machine. The mandrel wire 9 passes from the spool 7 across a resilient wiper 10 to a continuously rotating feed roll 11. The two legs of the resilient wiper 10 are lined with felt or similar soft material and serve for cleaning the mandrel wire. The latter passes around the feed roll 11 and thence goes downwards across the frame 1 and a plate 2 fixed thereto to a guide wheel 12 pivoted to the end of a housing 13.

The mandrel wire passes from the guide wheel 12 through a rotary winding head 14 and through a winding guide 15 which if

necessary is provided with a bored diamond, over guide wheels 16 and 17 pivoted to housings 18 and 19 back to the feed roll 11. The winding head 14 has mounted on it a supply spool 22 for carrying the winding wire which passes over a guide wheel 23 on the winding head and thence along the lower end of the winding guide 15 to the mandrel wire 9. The mandrel wire travels through the winding guide and as the winding head rotates, the winding wire is at this point helically wound on the mandrel wire 9.

The winding guide 15 may be heated at will by any suitable device that ensures that the winding wire which passes along the lower end of the winding guide 15, is heated to a high temperature. This may sometimes be desirable in order to prevent the winding wire from breaking during the winding operation. The winding wire may be heated by passing an electric current through it.

The mandrel wire with the winding wire wound on it passes from the feed roll 11 through a slot in a finger 24 to a spool 20 on a spindle 21 journaled in the housing 8. The spool 20 is driven at the desired velocity through a friction coupling and the finger 24 is periodically reciprocated by a heart shaped cam, so that the wound mandrel wire is wound on the spool 20 in regular adjacent coils. The mandrel wire prior and subsequent to the winding wire being wound on it passes over the same feed roll 11, which, as already observed, ensures a very regular movement of the mandrel wire and at the same time avoids breakage or too great a stretching of the said wire.

In order to ensure that the mandrel wire does not slip on the feed roll and that it consequently acquires accurately the same velocity as the latter, the unwound mandrel wire is pressed into engagement with the feed roll 11 by a roller 26 of steel or other hard material pivoted on one end of a lever 27 which is rotatable on a spindle 28. The other end of the lever 27 extends through the plate 2 and is pulled downwards by a spring 29, the tension of which can be regulated by a set screw 30. The end of the lever 27 to which the spring 29 is secured can be moved upwards against the action of the said spring and consequently the roller 26 can be thrown out by means of a catch having two pivotally connected legs 31 and 32 which are movable relatively to each other. When the leg 32 shown in Figure 2 is moved to the left, the pivot 33 of the two legs is moved horizontally to the left and thus the lever 27 is rotated against the pull of the spring 29.

The wound mandrel wire is pressed into engagement with the feed roll 11 by a belt

35 of leather or similar soft flexible material which passes over pulleys 36, 37 and 38. The pulley 36 is pivoted to an arm 39 which is rotatable on the spindle 28. The pulleys 5 37 and 38 are mounted in a frame 40 pivoted on the spindle 28 and pulled upwards at the left end (Figure 2) by a helical spring 41. The tension of the said spring can be 10 regulated by means of a set screw 42. By 15 means of this arrangement the belt 35 is pressed into engagement with the feed roll 11 at a tension of the desired value.

On passing over the feed roll 11 the wound mandrel wire acquires a slightly greater 15 velocity than the unwound mandrel wire because the wound wire by reason of the presence of the winding wire between the mandrel wire and the roll rotates around the longitudinal axis of the roll on a slightly 20 greater radius. In practice this has been found to present no difficulty if care is taken that the tension in the mandrel wire 9 between the spool 7 and the feed roll 11 is slight. The slightly greater velocity 25 acquired by the wound wire on the feed roll 11 is really advantageous, because it keeps the portion of the mandrel wire between the points of passing on and off the feed roll at the desired tension.

30 It is apparent from Figure 1 of the drawings that in the machine illustrated six adjacent winding heads with their corresponding sets of spools and other devices have been provided thereby permitting the machine 35 to wind six coils simultaneously. The mechanisms of all six winding sets are similar to that above described. Of course the number of winding heads illustrated by way 40 of example is by no means meant as a limit and a different number may be provided at will.

The manner of driving the machine from 45 the motor 45 is clearly shown in Figures 1, 3 and 4. Figures 3 and 4 show the frame 1 of the winding machine so mounted as to be entirely clear of the frame 3 which carries the driving shaft 46. The frames 1 and 3 are connected only by an endless belt 47 which transmits the revolution of the shaft 50 46 to various members of the winding machine. The vibrations of the frame 3 are consequently transmitted to only a very slight extent to the main frame 1 which is desirable, as the said vibrations may give 55 rise to irregularities in the coiling. The frame 3 rests on a bed plate 4 (Figures 3 and 4) on which the motor 45 (Figure 3) is mounted. The energy of the motor is transmitted by the endless belt 47 to the 60 driving shaft 46 and thence to pulleys 105 of the winding heads and to a pulley 49. The belt 47 is kept under tension by means of a weight 48 (Figure 4). The machine may of course be driven by means of several 65 belts but the use of one endless belt is to be

preferred because then there is only one joint which gives rise to vibrations to a much smaller extent than when using a number of belts having each a joint. The pulley 49 is rigidly mounted on a shaft 50 journaled 70 in bearings 51 and 52 (Figure 1) having between them a worm case in which a worm 53 on the shaft 50 meshes with a worm-wheel 54. This worm wheel is seated on a shaft 55 having also secured to it a cog-wheel 75 56, which gears with a cog-wheel 57. The latter cog-wheel is mounted on shaft 58 and gears with a cog-wheel 61 on a shaft 62. On the shaft 62 is also seated a worm 67 which engages with a worm-wheel 68 rigidly mounted on a shaft 69 which is integral with the feed roll 11 and drives it continuously. The position of the shaft 58 can be changed by means of a link 63 which is rotatable on the shaft 62 and which is provided with a slot 64 in which a stud 65 can slide. The link 63 is secured to the frame by a nut on the stud 65. By this mechanism cog-wheels 57 and 61 of different size may be used to change the velocity of the roll 11 and consequently that of the mandrel wire 9. The shaft 69 is journaled in bearings 70 and 71 and at the other end of the feed roll 11 is a shaft 80 journaled in a bearing 81.

The spools for winding the wound mandrel wire and the fingers 24 for reciprocating the mandrel wire are driven from the feed roll 11.

On the end of the shaft 80 is a sprocket wheel 82 (Figure 1) which by means of a chain 83 gears with a sprocket wheel 84 on a shaft 85 journaled in bearings 86. The shaft 85 has rigidly secured to it a number of friction clutches 88 (Figures 1 and 2) whereas cog-wheels 87 which engage with the said 105 friction clutches are rotatably mounted on it (Figure 2). The friction clutches 88 are provided with resilient fingers 89 (Figure 1) to engage a conical part of the cog-wheels 87 which are in mesh with cog-wheels 90 110 (Figure 2) rigidly attached to the spools 20 so that the spools 20 are driven from the shaft 85 through friction clutches.

On the shaft 69 of the feed roll 11 is a worm 72 which meshes with a worm wheel 73 on a shaft 74. A heart cam 75 on this shaft is thus continuously actuated so that a reciprocating movement is imparted to a lever 76 at the end of a shaft 25. The shaft 25 as shown in Figure 1 is normally drawn 120 to the right by a draw-spring 78. The fingers 24 are reciprocated with the shaft 25 and thus permitted to accomplish their function hereinbefore described.

The construction of the rotary winding heads which cooperate with the winding guides 15 to helically wind the winding wire on the mandrel wire is clearly shown in Figures 2, 5 and 6. Bushings 100 are rigidly secured in the plate 2 of the machine by 130

means of a set screw 101 (Figure 2). Within the said bushings the spindle 104 is rotatably journaled on ball bearings 102 and 103 (Figure 5). At the lower end of the said spindle is a pulley 105 provided with a flange 106 to prevent the belt 47 from running off. A cone 107 is rigidly secured to the upper end of the spindle 104 which is provided with a central bore 104' and carries and drives the winding head 14. When this spindle 104 is rotated, the winding head 14 which by its own weight rests with a conical smooth surface 108 on the cone 107 is carried along by it.

15 In addition a device has been provided which permits of stopping each winding head singly.

For this purpose a cone 110 is rotatably pivoted in the upper end of the bushing 100. 20 This cone can be rotated by means of a finger 111 and studs 112 secured to the cone slide in cam-slots 113 of the bushing 100. These cam slots are inclined, so that during the rotation of the finger 111 to one side, the cone 110 is forced upwards. Conical smooth surfaces 109 are thereby brought into engagement with each other so that the winding head 14 is lifted out of engagement with the cone 107. By reason of the friction between the surfaces 109 the winding head is soon stopped. On the end 114 of the winding head housings 116, 119, 121 and 122 (Figures 5 and 6) are mounted. The spool 22 (Figure 6) for the winding wire is journaled between the housings 116 and 119 and is for this purpose provided with a pivot 115 which is pivoted in a little block arranged within the housing 116. A pivot 117 enters the spindle of the spool 22. This pivot is arranged at the end of a spindle 118 which is reciprocatable in the housing 119. The pivot 117 is pressed into the spindle of the spool by a spring 120 which is secured to the housing 121 and the tension of which can be regulated by means of a set screw 122. The spool 22 is braked owing to the friction of the pivots in their blocks, which prevents the winding wire from hanging slack. A microscope 125 (Figure 2) is slideable on the prism guide 126, and consequently permits of inspection of the wound mandrel wire from each winding head.

What we claim as new and desire to secure by Letters Patent of the United States, 55 is:—

1. In a coiling machine, the combination with a rotary winding head, of means for directing a mandrel wire through said head, and a driving member in positive driving engagement with said unwound mandrel wire as it passes into and with the wound mandrel wire as it leaves said winding head.

2. In a winding machine, the combination with a rotary winding head, of a driving member for a mandrel wire, and means for

passing over said member in driving engagement therewith the unwound mandrel wire on its way into said head and the wound mandrel wire delivered from said head.

3. In a coiling machine, the combination 70 with a rotary winding head, of mandrel wire feed mechanism for passing a mandrel wire through said head comprising concentric cylindrical feed members having the same surface speed, and means for maintaining 75 both the unwound mandrel wire entering the winding head and the wound mandrel wire leaving it in feeding engagement with said members.

4. In a coiling machine, the combination 80 with a rotary winding head, of means for directing a mandrel wire through the head comprising a feed roll of uniform diameter in engagement with the unwound mandrel wire fed into said winding head and with 85 the wound mandrel wire delivered from said head.

5. In a coiling machine, the combination 90 with a plurality of winding heads side by side and rotatable about vertical axes, of means for passing a mandrel wire through 95 each head comprising a feed roll common to all said heads, and means for causing said roll to feed unwound mandrel wire into each head and wound mandrel wire away 100 from each head.

6. A coiling machine comprising a vertical plate, a plurality of winding heads mounted side by side on one side of said plate to be rotatable about vertical axes, 100 means for passing a mandrel wire through each head comprising a feed roll on the other side of said plate and common to all said heads, and means for causing said roll to feed unwound mandrel wire into each head and wound mandrel wire away 105 from each head.

7. A winding head comprising a vertical spindle having a conical upper end, a winding member having a corresponding conical 110 recess resting on said spindle and frictionally driven thereby, and means for driving said spindle at uniform speed.

8. A winding head comprising a vertical spindle having a conical upper end, a winding member having a corresponding conical 115 recess resting on said spindle and frictionally driven thereby, disengaging means for raising said member off the conical end of said spindle, and driving means for said 120 spindle.

9. In a winding machine, the combination 125 with a frame having mounted thereon winding heads, each with a driving pulley, and mandrel wire feed mechanism with a driving pulley, of a counter frame independent of said first frame and provided with a driving shaft belted to the driving pulleys of said heads and of said feed mechanism.

10. In a winding machine, the combina- 130

tion with a frame having mounted thereon a plurality of winding heads side by side, each with a driving pulley, and a mandrel wire feed mechanism having a driving pulley, of a counterframe independent of said first frame and provided with a driving pulley belted to all said driving pulleys on said first frame.

11. In a winding machine, the combination with a frame having mounted thereon a plurality of winding heads side by side each with a driving pulley, and mandrel wire

feed mechanism for passing mandrel wire through said heads, of a driving cylinder common to all of said heads, and perpendicular to the axes of rotation of said heads, and a single belt passing over each of said winding head pulleys and said cylinder successively.

In witness whereof, we have hereunto set our hands this 7th day of November, 1924.

RICHARD SHEPHERD.
WALTHER DALHEIMER.
